UNITED STATES PATENT OFFICE.

GUSTAV J. GRUENDLER, OF ST. LOUIS, MISSOURI.

REFRIGERATOR.

1,176,675.

Specification of Letters Patent. Patented Mar. 21, 1916.

Application filed June 1, 1914. Serial No. 842,247.

To all whom it may concern:

Be it known that I, GUSTAV J. GRUENDLER, a citizen of the United States, and resident of St. Louis, Missouri, have invented certain 5 new and useful Improvements in Refrigerators, of which the following is a specification containing a full, clear, and exact description, reference being had to the accompanying drawings, forming a part hereof.

10 My invention relates to improvements in refrigerators, and the object of my invention is to construct a refrigerator in such manner as to receive freezing cans wherein water may be frozen for the production of 15 ice which may be used either to recharge the refrigerator or for table or other uses.

With the above purposes in view my invention consists in certain novel features of construction and arrangement of parts as 20 will be hereinafter more fully described, pointed out in the claims and illustrated by the accompanying drawings, in which—

Figure 1 is a longitudinal sectional elevation of a refrigerator embodying my invention; Fig. 2 is a transverse sectional elevation taken on the line 2—2 of Fig. 1; Fig. 3 is a plan of a refrigerator having a portion of its top removed; Fig. 4 is a perspective illustrating my improved freezing can; 25 Fig. 5 is a perspective illustrating my improved brine tank arranged to receive the freezing can; Fig. 6 is a plan illustrating one of the ice-holding tubes; and Fig. 7 is a vertical section illustrating a removable 30 container for an auxiliary chemical freezing agency.

Referring by numerals to the accompanying drawings: 8 designates the body of the refrigerator which may be of any approved 40 construction having insulated walls and provided with doors such as 9 for gaining access to the interior thereof, and also a removable lid 10. Arranged beneath the lid 10 and projecting some considerable distance 45 into the interior of the refrigerator body there is an ice-container 11 having openings in its bottom through which are projected a plurality of open-ended tubes 12 which extend some considerable distance 50 downwardly into the interior of the refrigerator beyond the ice-container 11 and which also project upwardly some considerable distance into the ice-container. At the bottom of each of the tubes 12 there are 55 crossed bars 13 for the purpose of holding ice in the tubes yet permitting the water

from the molten ice to pass from the tubes. For the purpose of cleansing the tubes 12 may be removed upwardly through the container 11. Removably positioned within the 60 interior of the refrigerator adjacent the door 9 and immediately beneath all of the tubes 12 is a brine tank 14.

15 designates pockets, open at one end, which open end of the pockets registers with 65 openings 16 formed in an end wall of the brine tank. The bodies of the pockets 15 are separated from each other and all of the walls of the brine tank, except the one having the openings therein. These pockets 15 are arranged to receive the freezing cans 17, 70 each of which is in the form of a drawer having a drawer-pull 18 at its forward end. Each of these freezing cans is provided with a partition 19 whereby to form more rigid 75 side walls and in order that more than one piece of ice may be made at a time, which, because of its size, is more easily handled.

20 designates a pan having a perforated bottom which is arranged to fit over the top 80 of the brine tank and is arranged for the purpose of preventing large particles of salt or ice from the tubes 12 from falling to the bottom of the brine tank.

Arranged within the refrigerator and connected with the ice container 11 is a coil of pipe 21. This coil extends through the body of the refrigerator and is connected with a discharge pipe 22. Within the coil between the ice-container 11 and the discharge pipe 90 22 is a water trap 21^a arranged to hold a quantity of cold water from the molten ice of the container 11.

24 designates a pipe leading from the brine tank 14 and connected with the coil 23, 95 which coil includes a trap 23^a, and provides an overflow for the brine tank.

Secured to the bottom of the ice container 11 at its approximate center is an internally threaded ring 25 which registers with an 100 opening formed in the bottom of said ice-container, and constitutes a support for a metallic-bottle 26 which bottle has embracing it at its vertical center an externally threaded ring 27 and at its top a removable 105 closure 28. Such a bottle filled with brine and surrounded by the receptacles 12 will become quite cold while the mixture of ice and salt is melting. When such mixture has melted and drained away, the brine container 110 will act for a limited time as a heat absorber to keep the refrigerator cool. The

tubes next adjacent the bottle are of smaller size than the remaining tubes, as shown in Fig. 3, whereby the bottle may be hung between them.

5 The type of refrigerator shown is an ordinary commercial ice box and serves only to illustrate a practical housing for the apparatus of my invention.

In the practical operation of my invention, assuming the parts to be assembled as shown, a quantity of cracked ice and salt is placed in the container and in each of the tubes 12. By reason of the large area of exposed surface of the container and the tubes, 15 the interior of the refrigerator is cool and, by reason of the coils 21 and 23 carrying off the molten ice from the container 11 and brine tank 20, there is a further agent or means for reducing the temperature of the 20 interior of the refrigerator. The brine tank is located near the bottom of the refrigerator in the coldest zone thereof and is arranged to catch all of the brine from the molten ice and salt. Water or other matter to be 25 frozen is placed in the freezing cans and inserted in the pockets of the brine tank, where they are surrounded on all sides save one by the brine. This brine is sufficiently cold to freeze the water or other matter in 30 the cans.

A distinct advantage arising from the refrigerator having a zone wherein the temperature is below freezing point is that some ice may be formed and used for the purpose 35 of recharging the refrigerator, hence con-

serving ice. Another distinct advantage arising from this construction is that other materials for table or like uses may be frozen in the refrigerator. In order to provide for separate compartments and for controlling 40 the temperatures thereof, I arrange a partition within the refrigerator and place in the top and bottom thereof hinged doors.

I claim:

1. A refrigerator, comprising a number of 45 containers for ice and salt, a brine tank arranged to receive brine from said containers, there being pockets within said brine tank but not in communication therewith, and removable freezing cans arranged to be held 50 in said pockets.

2. A refrigerator, comprising a hollow body, an ice container therein, a coil of pipe arranged for the drain of said container, a plurality of tubes in communication with 55 said container, a brine tank arranged to receive water from said tubes, there being pockets formed in said brine tank but not in communication therewith, removable freezing cans arranged to be held in said pockets, 60 and an overflow pipe for said brine tank connected with said coil of pipe.

In testimony whereof, I have signed my name to this specification, in presence of two subscribing witnesses.

GUSTAV J. GRUENDLER.
